2 Sheets-Sheet 2

UNITED STATES PATENT OFFICE.

CHARLES W. SMART, OF MEMPHIS, TENNESSEE.

WATER-TUBE BOILER.

Application filed March 16, 1923. Serial No. 625,658.

To all whom it may concern:

Be it known that I, CHARLES W. SMART, a citizen of the United States, residing at Memphis, county of Shelby, and the State of Tennessee, have invented certain new and useful Improvements in Water-Tube Boilers, of which the following is a full, clear, and exact description, such as will enable anyone skilled in the art to make 10 and use the same.

My invention relates to stationary boilers primarily designed for generating steam for heating purposes but it may be readily adapted to a boiler for power purposes by 15 the introduction of stay bolts or other braces which are not necessary in the case of low pressure boilers, such as are used for heating purposes. My boiler also may be used if it be so desired, for hot water heating.

The objects of my invention are to provide, first, an arrangement of boiler and tubes and baffle walls therefor which will more efficiently remove the heat from the products of combustion of the fuel and second, to provide means for supplying and burning the fuel which may be efficiently regulated in accordance with the uses of the steam for heating or power purposes.

I accomplish these objects as will be more fully hereinafter set out in the drawings, specification and claims, to which reference is now made.

In the drawings:

Fig. 1 is a side elevation of my improved boiler and the setting therefor.

Fig. 2 is a plan view of the exterior of the boiler and setting.

Fig. 3 is a front elevation of the boiler.

Fig. 4 is a vertical section of the boiler and setting taken on the line IV—IV of Fig. 2 looking in the direction of the arrows.

Fig. 5 is a vertical sectional elevation on the line V—V of Figs. 4 and 6.

Fig. 6 is a horizontal sectional plan on the line VI—VI of Fig. 4.

Referring now to the drawings in which the various parts are indicated by the same numerals in all the views, the boiler proper 50 has a fuel container in the shape of a truncated pyramid preferably of rectangular horizontal cross section having a back 17 and front 17' and sides 16—16'; this container being of smaller cross section at the 55 top than at the bottom and being provided

with a closely fitting cover or top 28 which may lie thereon or be hinged thereto as shown. This container forms an inner shell for the boiler. Surrounding this fuel container and preferably uniformly spaced 60 therefrom is the outer shell of the boiler having a front 14, a back 14' and sides 15—15'; this outer shell being welded, riveted or otherwise securely fastened to the inner shell near the top and bottom thereof. In 65 the drawings these inner and outer shells of the boiler are shown at the bottom as one continuous sheet.

The sides of the inner shell and the sides 70 portions of the outer shell form legs which extend below the corresponding front and back portions, though if desired, the front may extend to the same level as the sides. The back portion 14' of the outer shell is curved backward intermediate its height to 75 form a larger water chamber, and is thence reversely bent and extended vertically upward as shown more clearly in Fig. 4. This vertical section extends practically to the top of the inner shell and is thence bent 80 horizontally forward and welded or otherwise secured thereto. Likewise the sides 15—15' are extended rearwardly and joined up to this back portion 14' to complete the 85 water chamber. From the lower end of the rear leg formed between the shell 14' and the inner shell 17 vertical tubes 32 extend downward to a cross header 31 which extend between the two side legs and connects the same. From the back of the rear 90 leg, water tubes 30 extend rearwardly rising at a slight angle from the horizontal and are then sharply bent upwardly and through substantially a half circle and extend forward rising at a slight angle from 95 the horizontal to the enlarged water chamber of the boiler into which they connect.

Similarly tubes 29 extend from the cross header 31 rather sharply upward until they come into proper relation to the tubes 30 100 and thence extend parallel with that set of tubes into the same water chamber. Between the rearwardly extending and the forwardly extending portion of these water tubes is a horizontally disposed baffle or fire wall preferably having its lower and upper surfaces substantially parallel to the tubes. This baffle wall is preferably made up of a number of individual sections 5, 6, 7 and 8 which sections as will be seen by 105 110

reference to Fig. 1, preferably extend through the side walls 9 of the flue chamber. These baffles are thus made in sections for the purpose of reducing the size 5 of them to such extent that they may be precast and put in place by hand. This baffle wall may be of fire clay or other refractory material, I having found that cinder concrete is admirably adapted for the 10 purpose. The flue chamber for the boiler is composed of this central baffle wall a foundation or base 3 preferably also of cinder concrete, side walls made up of sections 4, 9 and 10 shown in Fig. 1 of the 15 drawings, a top 11 and a rear wall composed of sections 12 and 13. This rear wall may be made of a single section instead of the two sections shown and is preferably removable so that it may be used as a door 20 to permit access to the back of the flue chamber should such access be desired. 38 and 39 are removable blocks which complete the side inclosure of the flue chamber, and which may be opened for cleaning. 37 (Fig. 4) on the opposite side of the flue chamber is the flue and 37' a continuation of the same.

Air for combustion is admitted through an air inlet 25 which extends through both 30 the outer front shell 14 of the boiler and the front 17' of the fuel container and is disposed above the grates and inclined downward so that fuel will not be held up therein. This air inlet is provided with a 35 door 26 preferably hinged at the top to the front shell 14. This door may be opened or closed by means of the chain 27 shown in Figs. 1 and 3 which chain if desired may be extended upward to some form of regulating device not shown. The grates for the 40 boiler preferably are provided with a rocker shaft 36 preferably of square section extending from side to side and beyond one of the sides so that some form of arm or shaker 45 may be slipped thereon to rock the same, on which shaft are mounted grates made up of a plurality of identical sections each having three fingers or bars 33, 34 and 35 extending from a hub shaped to slip over the 50 shaft 36 so that when the shaft is oscillated the grates will be similarly oscillated. If desired a number of these sections each containing three bars may be united by a single hub as shown in Fig. 5.

55 Immediately below the grates is an ash pit having rear and front walls 1-1', a bottom 2, and suitable ends, and provided with a door 40 for access thereto. It is essential that this pit be tightly closed so 60 that air will be only admitted through the air inlet 25 above the grates. 18 and 19 are stoker holes through one side of the boiler and fuel container wall. These stoker holes are closed by doors 18' and 19' more clearly 65 shown in Fig. 5. 21 is a water glass pro-

vided with the usual gage cocks 22 and 23. 24 is the steam pipe leading from the top of the boiler and 20, shown in Fig. 4 the opening for the return pipe or water inlet.

The boiler having been installed and filled 70 with water up to near the top of the gage glass, kindling is preferably placed on the grate bars 33-34 and coal put in from the top by opening the cover 28. Fire having been started the fuel container is preferably 75 filled to the top, air is admitted through the air inlet 25 by opening the door 26 the desired amount, the fire being regulated by the amount of air admitted through this 80 opening. After the fire has burned for some time, the grates can be shaken slightly to break up the fire in the usual manner or a stoker bar may be introduced through the stoke holes 18, 19 for this purpose. When 85 it is desired to get rid of ashes which may have accumulated on the grate, the rocker shaft 36 may be given a quarter turn and the ashes held in one quadrant, or the grates dumped and a new quadrant be brought under the fire, this process being reversed when 90 it is again desired to dump the grates. Air passing through the bed of fuel is entirely 95 above the grates and carries with it the production of combustion into the edge of the flue chamber where the combustion is completed and additional intense heat generated. These heated gases then pass along the tubes underneath the baffle wall and around the end of the same and thence pass forward still following the tubes to the flue 100 37 through which they pass outward. It will be seen that the furnace gases are thus held in intimate contact with the water tubes and are given every chance to transfer their 105 heat to the water within the tubes.

110 It will be seen that the shape and disposition of the tubes provide every facility for expansion and contraction as well as for circulation of the water within the same. The ashes dumped may of course be removed from the ash pit at any time desired. Access may be had to the flue chamber by removing either the door 38 or 39 or the rear wall 12. In addition, it is possible if it 115 should become necessary to remove the side walls in sections or to remove the top 11 of the flue chamber. Should the baffle wall burn out, the various sections thereof may be individually removed through the side 120 walls of the flue chamber.

Having now fully described my invention what I claim and desire to secure by Letters Patent of the United States is:—

1. In a furnace, the combination with a 125 hollow boiler having an interior shell of truncated pyramidal form and rectangular cross section forming a fuel compartment, with the back section of said shell terminating above the side sections thereof, a fuel opening in the top of said compartment and 130

pairs of vertically aligned substantially U shaped tubes extending rearwardly, the lower end of one tube of each of said pairs from said header, and of the other from the 5 rear of said back water leg near the bottom thereof, and the upper ends of both tubes of each of said pairs connecting into the back of said enlarged water compartment, and an air inlet leading through the front water leg of said boiler into the lower portion 10 of said fuel compartment.

5. A hollow boiler having an interior shell larger at the bottom than the top forming a fuel compartment, with the back portion 15 of said shell terminating above the side sections thereof, a fuel opening in the top of said compartment and a cover for the same, an exterior shell having the front, sides and the lower portion of the back thereof 20 conforming in cross section to said interior shell and spaced therefrom, and having the upper portion of the said back shell extended rearwardly to form an enlarged water and steam compartment, a cross header connecting the 25 water legs formed between the side shells near the bottom thereof, a plurality of vertical tubes connecting the bottom of the water leg, formed between the back shells, and the said cross header, and a similar number of 30 vertically aligned pairs of substantially U shaped tubes extending rearwardly, the lower end of one tube of each of said pairs from said header, and of the other from the rear of said back water leg near the bottom 35 thereof, and the upper ends of both tubes of each of said pairs connecting into the back of said enlarged water compartment, and an air inlet leading through the front water leg of said boiler into the lower portion 40 of said fuel compartment.

6. In a furnace, the combination with a hollow boiler having an interior shell forming a vertical fuel compartment, with the back portion of said shell terminating above 45 the side sections thereof, a fuel opening in the top of said compartment and a cover for the same, an exterior shell having the front, sides, and lower portion of the back thereof conforming in cross section to said interior shell and spaced therefrom, and having the 50 upper portion of the said back shell extended rearwardly to form an enlarged water and steam compartment, a cross header connecting the water legs formed between said side shells near the bottom thereof, a plurality of vertical tubes connecting the bottom of the water leg, formed between said back shells, and the said cross header, and a similar number of 55 pairs of vertically aligned substantially U shaped tubes extending rearwardly, the lower end of one tube of each of said pairs from said header, and of the other from the rear of said back water leg near the bottom 60 thereof, and the upper ends of both tubes of each of said pairs connecting into the back of said enlarged water compartment, of grates beneath said fuel compartment, vertically aligned stoke holes leading through one side water leg and an air inlet leading through the front water leg of said boiler, all leading into the said fuel compartment above said grates, and a flue chamber extending rearwardly from said exterior shell and surrounding said tubes, said flue chamber being divided into a rearwardly directed and a return section by a baffle wall extending rearwardly from the lower end of the rear water leg of said boiler into the bend in 65 said U shaped tubes.

of each of said pairs from said header, and of the other from the rear of said back water leg near the bottom thereof, and the upper ends of both tubes of each of said 65 pairs connecting into the back of said enlarged water compartment, of grates beneath said fuel compartment, an air inlet leading through the front leg of said boiler into said fuel compartment above said 70 grates, and a flue chamber extending rearwardly from said exterior shell and surrounding said tubes, said flue chamber being divided into a rearwardly directed and a return section by a baffle wall extending 75 rearwardly from the lower end of the rear leg of said boiler into the bend in said U shaped tubes.

7. In a furnace, the combination with a hollow boiler having an interior shell of truncated pyramidal form and rectangular cross section forming a fuel compartment, with the back section of said shell terminating above the side sections thereof, a fuel opening in the top of said compartment and a cover for the same, an exterior shell having the front, sides, and lower portion of the back thereof conforming in cross section to said interior shell and uniformly spaced 80 therefrom, and having the upper portion of the said back shell extended rearwardly to form an enlarged water and steam compartment, a cross header connecting the water legs formed between said side shells near the bottom thereof, a plurality of vertical tubes connecting the bottom of the water leg, formed between said back shells, and the said cross header, and a similar number of 85 pairs of vertically aligned substantially U shaped tubes extending rearwardly, the lower end of one tube of each of said pairs from said header, and of the other from the rear of said back water leg near the bottom 90 thereof, and the upper ends of both tubes of each of said pairs connecting into the back of said enlarged water compartment, of grates beneath said fuel compartment, vertically aligned stoke holes leading through one side water leg and an air inlet leading through the front water leg of said boiler, all leading into the said fuel compartment above said grates, and a flue chamber extending rearwardly from said exterior shell and surrounding said tubes, said flue chamber being divided into a rearwardly directed and a return section by a baffle wall extending 95 rearwardly from the lower end of the rear water leg of said boiler into the bend in said U shaped tubes.

In testimony whereof I have hereunto set 100 my name.

CHARLES W. SMART.
